UNITED STATES PATENT OFFICE.

WILLIAM H. BROWN, OF NEWARK, OHIO.

SAFETY-STOP FOR LOCOMOTIVES.

No. 894,113.

Specification of Letters Patent.

Patented July 21, 1908.

Application filed October 15, 1907. Serial No. 397,569.

To all whom it may concern:

Be it known that I, WILLIAM H. BROWN, a citizen of the United States, residing at Newark, in the county of Licking and State of Ohio, have invented certain new and useful Improvements in Safety-Stops for Locomotives; of which the following is a specification.

This invention contemplates certain new and useful improvements in railway safety appliances and relates particularly to an improved mechanism for automatically bringing a train to a standstill, should a danger signal be set and the engine driver, through neglect or carelessness run past the signal, and more specifically, the invention consists in an improved construction of mechanism designed to automatically shut off the steam by the actuation of the engine throttle, at the same time blow the whistle to apprise the engineer of the actuation of the mechanism and at the same time give warning in other ways, and throw the handle of the engineer's brake valve to the emergency position, so as to throw on the brakes and quickly bring the train to a standstill.

The invention has for its object an improved construction of mechanism of this character which is under the control of a single operator or switchman at the signal tower or switch stand, and which will act positively and otherwise efficiently when the trip bar along the track is set in operative position.

For a full understanding of the invention, reference is to be had to the following description and accompanying drawings, in which:

Figure 1 is a side elevation of the rear portion of the locomotive equipped with the improvements of my invention, the track apparatus being shown in perspective for the sake of clearness; Fig. 2 is a similar view on an enlarged scale, the locomotive itself being omitted and the parts shown in operating position; Fig. 3 is a longitudinal sectional view of the throttle lever actuating parts of the apparatus; Fig. 4 is a transverse sectional view through the track mechanism; Fig. 5 is a perspective view in the nature of a diagram, illustrating the operative relations between my invention and the signal mechanism. Fig. 6 is a detail perspective view of a modified arrangement of the track devices, hereinafter specifically referred to.

Corresponding and like parts are referred

to in the following description and indicated in all the views of the drawings by the same reference characters.

Referring to the drawings, the numeral 1 designates the track rails and 2 the ties.

3 designates a trip bar which is arranged alongside one of the track rails 1 and which is pivotally connected at its ends to two sections 4 and 5, designed, when the trip bar is set, to lead upwardly thereto, and downwardly therefrom, respectively, so as to prevent any sudden jar of the actuating mechanism. The section 4 may be connected to a fixed pivot on the plate 6 secured to one of the ties, while the other section 5 is mounted for a sliding movement by being connected at its outer end to the rod 7 movable longitudinally in the bearing plate 8.

Any desired mechanism may be employed for raising and lowering the trip bar 3. For instance, as illustrated in Fig. 5, I may secure cranks 9 to the trip bar, said cranks projecting from shafts that are journaled in any suitable bearings on the ties and that are connected by any suitable combination of bell cranks and link rods 11 to the actuating rod 12 leading to the tower or switch-stand and under the control of the signal operator or switchman. For the purpose of illustration, I have shown the actuating rod 12 as connected by bell crank and link with the semaphore or other signal 13, in such a manner that as the signal is moved to the danger position, the trip bar 3 will be raised above the track. When the signal is moved to the safety position, the switch bar will be depressed and will preferably lie in a plane below the upper surface of the track rails 1. If desired as illustrated in Fig. 6, I may provide guard rails 3^a arranged alongside of the trip bar and its related parts so as to protect the same, said guard rails in this instance being provided with an apertured ear for the shafts that carry the cranks 9. Or, as illustrated in Figs. 1 and 2, the actuating rod 12 may lead off to any desired point for the operation of the trip bar 3.

14 designates a wheel or roller that is designed to ride upon the trip bar 3 with the latter in elevated position so as to effect the actuation of the parts of the apparatus and said roller is journaled in one end of the lever 15 fulcrumed intermediate of its ends on a frame 16 secured in any desired manner and projecting preferably below some portion of the locomotive cab C. A helical spring 17 is

mounted underneath the other arm of the lever 15 so as to hold said lever under tension in operative position and insure the proper working of the parts, and a guide loop 18, preferably extends over this arm of the lever so as to hold the lever in place. A link 19 connects the lever 15 with an arm 20 which is secured to the turning plug 21 of the valve 22. This valve is mounted in a branch pipe 23 leading from the train line pipe 24. In the normal position of the parts, the plug 21 is closed so as to shut off the communication from the train pipe to the branch 23, but when the roller 14 rides upon the trip bar 3 15 and the lever 15 is thereby rocked, the arm 20 is pulled downwardly so as to turn the plug into a position where it will establish communication between the train pipe 24 and the branch 23 and permit air to flow to 20 the cylinder 25 with which one end of said branch pipe 23 is connected. This cylinder is mounted within the cab and contains a piston 26 which is pressed rearwardly in the cylinder by means of a coil spring 27 around 25 the piston rod 28. This rod is provided at its outer end with a yielding section 29 designed, when the piston is forced forwardly by the admission of air pressure into the cylinder, to engage the upper end of a throttle 30 moving lever 30 fulcrumed on the throttle lever 31. The lever 30 is provided with a toe 32, and the detent 33 of the throttle lever is provided with a lug 34 designed for engagement by the toe 32 so as to free the detent 35 from the quadrant 36 and permit the continued pressure of the piston rod 28 on the throttle lever 31 to move the latter in a direction to shut off the steam. A spring 37 holds the lever 30 yieldingly in position on the 40 throttle lever 31.

In addition to the means for automatically shutting off steam, above described, my invention comprehends means for automatically applying the brakes. Such means comprises a spring connection 38 between the link rod 19 and one arm of a bell crank 39 fulcrumed, as indicated, at 40 at some convenient point in the locomotive cab; the other arm of the bell crank 39 is connected by 45 a link 41 with one arm of the lever 42. The other arm of this lever is provided with a spring extension 43 designed to engage the handle 44 of the engineer's brake valve of any desired or conventional construction, so 50 as to move said handle to emergency position and put on the brakes when the lever 13 is rocked, as above described.

In order to apprise the engineer, should he 55 pass a signal or danger point on a system equipped with my invention, that the automatic stop mechanism has been set and is working, a cord 45 is connected at one end to one arm of the bell crank 39, the other end of said cord being connected to the bell crank 46 fulcrumed, say, in the roof of the cab and

operatively connected by the cord 47 to the handle of the whistle 48.

From the foregoing description in connection with the accompanying drawings, it is obvious that when a signal is set to the danger position at any point along the track of a railroad equipped with my invention, the trip bar 3 will be at once raised to the operative position in readiness to actuate the various mechanisms above described. Even 70 should the engineer of an on-coming train, through carelessness, or negligence, pass the danger point, it is clear that the roller 14 riding upon the trip bar 3, will rock the lever 15 and pull downwardly upon the link rod 19 which will effect the admission of train pipe air to the cylinder 25 and consequently automatically move the throttle lever to the release position, and at the same time the air 75 brake will be set and the whistle blown. 80

Preferably, in order to absorb or prevent shock and increase the longevity of the parts of the mechanism, the various springs hereinbefore described and illustrated in the 85 drawings are provided.

It is to be noted that by the provision of the safety mechanism of my invention, all necessity of derailing devices are done away with, thereby saving the railroad the loss consequent upon the derailment of a train to 90 avoid a collision. 95

Having thus described the invention, what is claimed as new is:

1. In safety stop mechanism for locomotives, the combination of a trip bar, a lever 100 carried by the locomotive and arranged to be rocked by said bar, a link rod connected to one arm of said lever, the train line provided with a branch pipe, a valve in said branch pipe, the plug of said valve being provided 105 with an arm connected to said link rod, a cylinder connected to said branch pipe, a spring retracted piston mounted to reciprocate in said cylinder, a rod to which said piston is connected, said piston rod extending 110 out of the cylinder and provided at its outer end with a spring section, the throttle lever, and another lever fulcrumed upon the throttle lever and yieldingly mounted thereon, said last named lever having one arm in the 115 path of movement of said piston rod, being designed for engagement thereby to swing the throttle lever to the "shut-off" position.

2. In safety stop mechanism for locomotives, the combination of a trip bar, an actuating lever carried by the locomotive and arranged to be rocked by said trip bar, a link 120 connected to one arm of said lever, the throttle lever, the engineer's brake valve lever or handle, means for swinging the throttle lever and engineer's brake valve lever to the "shut-off" and brake-applying positions, respectively, an operative connection between said link rod and both of such means, whereby the rocking of the first named lever will 125 130

simultaneously effect the said movements of both the throttle lever and engineer's brake valve lever, the operative connection between the means for swinging the engineer's brake valve lever and the link rod including a bell crank, and an operative connection between said bell crank and the whistle of the locomotive.

3. In safety stop mechanism for locomotives, the combination of a trip bar, an actuating lever carried by the locomotive and arranged to be rocked by said trip bar, a link rod secured to one arm of said lever, a lever provided with a spring extension adapted to engage the handle of the engineer's brake valve to move the same to a brake applying position, and a link connection between said last named lever and the bell crank.

4. In safety stop mechanism for locomotives of the character described, a trip bar adapted to be raised and lowered in proximity to one of the track rails, hinged sections secured to the end of said trip bar, a support for the outer end of one of said sections and having a fixed pivot connection therewith, a rod pivotally connected to the outer end of the other section, a support in which said rod is mounted to slide, and means for raising and lowering said trip bar.

5. In safety stop mechanism for locomotives, the combination of a trip bar, an actuating lever carried by the locomotive and arranged to be rocked by engagement with said trip bar, a link rod connected to one arm of said lever, an air pressure cylinder, a branch connection between said cylinder and the train pipe of the locomotive, a valve in such branch connection, a connection between said valve and said link rod whereby the actuation of the lever in one direction will turn said valve to the open position, a spring retracted piston mounted in said cylinder, a throttle lever, a piston rod connected to said piston and adapted to release and move said throttle lever in one direction upon the admission of compressed air into the cylinder, an engineer's brake valve, a handle therefor, an actuating lever adapted to move said handle in one direction, a bell crank connected to said last named lever, a connection between said first named link rod and the bell crank, a whistle provided with a handle, and an operative connection with said bell crank and said handle.

In testimony whereof I affix my signature in presence of two witnesses.
